TABLE

Morton R. Cohen, Chicago, Ill.

Application August 12, 1957, Serial No. 47,307

Term of patent 14 years

(Cl. D33—14)

Fig. 1 is a perspective view of a table showing my new design.

Fig. 2 is an elevational view of the same on an enlarged scale; and

Fig. 3 is a detailed side elevational view of the upper portion of the same rotated through approximately 90°.

The dominant features of my design reside in those portions shown in full lines on the drawing.

The legs not shown are like the leg shown but are indicated in dotted lines for illustrative purposes only.

The design is principally characterized by the open-work configuration of the brace.

I claim:

An ornamental design for a table, substantially as shown and described.
